UNITED STATES PATENT OFFICE

WHIPPLE O. PARROTT, OF CHICAGO, ILLINOIS

PLAY DEVICE

Application filed May 16, 1929. Serial No. 363,456.

My invention relates to play devices and particularly to suspended play devices, and has for an object to provide a device for carrying an occupant, adapted to swing in a plurality of different ways.

Another object of the invention resides in providing a support and in suspending from said support a plurality of hangers, said hangers carrying a seat adapted to swing relative to the support.

A still further object of the invention resides in constructing the support with a pair of supporting members, and in adjustably connecting the ends of said hangers to said supporting members so as to permit of varying the angular relation of said hangers to cause the seat to swing in various ways.

A still further object of the invention resides in connecting the lower ends of said hangers to said member, and in constructing said hangers so as to permit of reversing the position of said member to interchange the positions of the ends of said hangers.

A still further object of the invention resides in forming said member with a seat on each side thereof, one of said seats being adapted to become disposed in operative position for each of the positions of said member.

Other objects of the invention reside in the novel combination of parts and in the details of construction hereinafter illustrated and described.

In the drawings:

Fig. 1 is a side elevational view of a play device illustrating an embodiment of my invention.

Figs. 2 and 3 are views similar to Fig. 1 illustrating the parts in various positions.

Fig. 4 is a fragmentary plan view of the structure shown in Fig. 1 drawn to a larger scale.

Fig. 5 is a sectional detail view of the lower end of one of the hangers illustrating the method of attachment thereof to the seat supporting structure.

My invention comprises primarily a support A from which is suspended a plurality of hangers 10 and 11 carrying at their lower end a seat structure B. The hangers 10 and 11 are adapted to be adjustably positioned relative to the support A so as to cause the seat structure B to swing in a number of different ways simulating in some respects the natural movement of leaping animals. The seat structure B is constructed so as to provide several seats adapted to be quickly brought into operative position at the will of a user. The construction and use of various parts of the invention will now be described in detail.

The support A consists of end frame members 12 and 13 which comprise uprights 14 and 15 connected together at their lower ends by means of transverse bars 16 and 17 and at their upper ends by means of transverse frame members 18 and 19. The uprights 14 and the transverse frame members 18 and 19 are preferably constructed of angle iron while the bars 16 and 17 may be constructed of strap iron or of any other shape desired. In addition to the end frame members 12 and 13, I employ longitudinal frame members 20 and 21 which are secured to the uprights 14 and 15 at their upper ends. The entire support is rigidly braced by means of braces 22 and 23 which are connected to the various uprights 14 and 15 and to the longitudinal frame members 20 and 21 and the transverse frame members 18 and 19 respectively.

Near the longitudinal frame member 21 are arranged two spaced parallel rods 24 and 25 which are attached to the transverse frame members 18 and 19. These rods extend through the depending flanges 26 thereof and are held from longitudinal movement in respect to said flanges by means of cotter keys 27. Two similar rods 28 and 29 are attached to the said transverse frame members in the same manner as the rods 24 and 25, and are positioned adjacent the longitudinal frame 20

member 20. These rods form supporting members from which the hangers 10 and 11 are suspended in a manner to be presently described.

5 The hangers 10 and 11 may be constructed from chains as illustrated in the drawings or the same may be made of rope or linked rods as desired. In the form of the invention shown, I have illustrated said hangers attached to rings 30, 31, 32 and 33 which are 10 slideable along the rods 24, 25, 28 and 29 respectively.

The seat structure B in the embodiment of the invention illustrated is in the form of the 15 body of a horse and is provided on the upper portion thereof with a saddle 34 serving as a seat, adapted to comfortably carry the occupant. The seat structure may be constructed in a fanciful manner by including a 20 horse's head 35 or by employing any other construction simulating in appearance the body or head of an animal. The underside of the seat structure B is preferably hollowed out as designated in dotted lines at 36 in Figure 25 3 and is formed in addition with a second seat 37. Upon inverting the seat structure B, the seat 37 becomes disposed uppermost as indicated by dotted lines at 38 in Figure 3 in which case the space 36 within the body of 30 the animal serves as a compartment for the reception of the occupant's feet. If desired, the seat 37 may be constructed similar to the seat 34 so as to require the occupant to straddle the body B the same as is required with 35 the seat 34 and the seat structure provided with the head of an animal such as a lion or tiger in identically the same manner as the horse's head 35. It can readily be comprehended that various kinds of animals may be 40 utilized with the invention in place of the plain seat 37 or the saddle 34 without departing from the spirit of the invention.

For the purpose of supporting the seat structure B the same is formed with four outwardly extending arms 39, 40, 41 and 42 issuing from the two sides of the same at the rearward and forward portions thereof. These arms may be formed by extending two rods through the body of the seat structure or 45 in any other desirable manner. The ends of these arms are provided with grooves 43, best shown in Figure 5, which are adapted to receive rings 44 attached to the lowermost ends of the chains 10 and 11. By means of this construction the seat structure B is supported in such a manner as to permit of the swinging thereof relative to the support A and of inverting the seat structure as will be hereafter described.

50 The hangers 10 and 11 are adjustably supported upon the rods 24, 25, 28 and 29 and may be adjusted and held in adjusted position by means of a structure illustrated in Figure 4. The upper portion of each of the rings 30, 55 31, 32 and 33 is formed with an attaching

member 45 to which is securely fastened at suitable intervals a cable 46. Cable 46 is adapted to pass about a pair of pulleys 47 and 48 attached to the transverse frame member 18 and in addition about other pulleys 49, 50, 51 and 52 attached to the transverse frame member 19. These various pulleys are so positioned as to divide the cable 46 into four spaced parallel longitudinal runs 53, 54, 55 and 56 which extend along rods 24, 25, 28 and 29 in parallel superimposed relation thereto. By means of two other pulleys 57 and 58, ends of the cable 46, which I have designated at 59, may be brought down along the upright 15 and secured thereto by means of a cleat 60 60 attached to said upright.

In the use of the device, the occupant has the choice of either of the seats 34 or 37 by merely inverting the seat structure B. This is permitted through the swivel connection 65 of the rings 44 to the arms 39, 40, 41 and 42. By adjusting the points of attachment of the hangers 10 and 11 with respect to the various rods 24, 25, 28 and 29 the angular position of the chains 10 and 11 may be varied 70 at will. This is accomplished by pulling on one or the other of the ends 59 of the cable 46 which moves the rings 30 and 32 in one direction and the rings 31 and 33 in the opposite direction. After the hangers have been 75 properly positioned, the same may be held from movement by securing the ends of the cable to the cleat 60 in the usual manner.

By varying the points of suspension of the hangers 10 and 11 relative to the supporting members 24, 25, 28 and 29 different effects 80 may be had in the swinging of the seat structure B. When the two hangers 10 and 11 are parallel as indicated by full lines in Figure 1, the seat moves in a parallel manner with 85 respect to the ground, raising slightly at the two ends of its course. By spreading the two sets of hangers as shown by dotted lines at 61 in Figure 1 the forward portion of the seat structure is caused to drop while the rearward portion is caused to raise as the seat reaches the end of its course. This gives the seat structure a movement simulating that produced by a bucking horse. When the two sets of hangers 10 and 11 are crossed as designated in full lines in Figure 2, the forward portion of the seat structure raises at the end 90 of the course and the rearward portion drops. This gives the seat structure a movement simulating that of a rearing horse. When the upper ends of the hangers 10 and 11 have been spaced a distance equal to the distance 95 between the respective lugs 41 and 42, the seat structure B will assume the position shown in dotted lines at 62 in Figure 2 when at its uppermost position. The degree of rearing or bucking desired may be regulated by varying the distance apart of the points of attachment of the hangers to the support. The greater this distance the greater the buck- 100

ing or rearing action. When the rings 30, 31, 32 and 33 are directly opposite one another, as indicated in full lines in Figure 3, the seat structure B swings in the arc of a circle similar to an ordinary swing.

When it is desired to utilize the seat 37, the seat structure B is merely inverted to take the position shown in Figure 3. This is readily accomplished by means of the swivel connection between the arms 39, 40, 41 and 42 and the hangers 10 and 11. When the seat structure is so positioned, the hangers 10 and 11 may be adjusted by means of the cable 46 to cause the said hangers to occupy any of the relative positions had by the seat structure in its other position so that either seat may be used and so that the seat structure may be caused to swing in any of the various ways described in conjunction with the other seat.

My invention is highly advantageous in that a simple and effective device is produced whereby considerable diverse amusement may be had by the occupant. The seat structure may be readily constructed to simulate various animals and can be readily manipulated to bring either of the seats into operative position. The hangers of the seat are readily and conveniently adjustable with respect to one another to vary the movement of the seat structure to simulate the natural movements of leaping or running animals.

Changes in the specific form of my invention, as herein disclosed, may be made within the scope of what is claimed without departing from the spirit of my invention.

Having described my invention, what I claim as new and desire to protect by Letters Patent is:

1. A play device comprising a support including a pair of supporting members adapted to rest upon the ground and to extend upwardly therefrom, a pair of hangers suspended from said supporting members and slidably relative thereto, a seat carried by said hangers and adjusting means connected with said hangers and extending downwardly along one of said supporting members for sliding said hangers, said means being operable from the ground.

2. In a play device, a seat arranged to swing in a front to back direction, two guides extending in a front to back direction and coextensive for a portion of the length thereof, members independently slidable along the coextensive portions of said guides, a hanger secured to one of said members and to said seat at the forward portion thereof, and a second hanger secured to said second member and to the seat at the rearward portion thereof.

3. In a play device, a seat arranged to swing in a front to back direction, two guides extending in a front to back direction and coextensive for a portion of the length thereof, members independently slidable along the

coextensive portions of said guides, a hanger secured to one of said members and to said seat at the forward portion thereof, and a second hanger secured to said second member and to the seat at the rearward portion thereof, and means attached to said members for simultaneously moving said members in opposite directions along said guides.

4. In a play device, a seat arranged to swing in a front to back direction, two guides extending in a front to back direction and coextensive for a portion of the length thereof, members independently slidable along the coextensive portions of said guides, a hanger secured to one of said members and to said seat at the forward portion thereof, and a second hanger secured to said second member and to the seat at the rearward portion thereof, a pulley at one end of said guide, and a cord passing over said pulley and having two reaches, one being attached to one hanger and the other reach to the other hanger for moving said members in opposite directions along said guides.

5. In a play device, a seat arranged to swing in a front to back direction, four guides extending in a front to back direction and coextensive for a portion of the length thereof, members independently slidable along the coextensive portions of said guides, a pair of hangers secured to two of said members and to said seat at the forward portion thereof, a second pair of hangers secured to the other two of said members and to the seat at the rearward portion thereof, two pulleys at corresponding ends of said guides and a cord passing about said pulleys and having pairs of reaches movable in opposite directions, means at the other ends of the guides for further guiding the cord the members connected to the forward portion of the seat being movable by reaches of said cord traveling in one direction and the other members being movable by reaches of said cord traveling in the opposite direction.

6. In a play device, a seat arranged to swing in a front to back direction, four guides extending in a front to back direction and coextensive for a portion of the length thereof, members independently slidable along the coextensive portions of said guides, a pair of hangers secured to two of said members and to said seat at the forward portion thereof, a second pair of hangers secured to the other two of said members and to the seat at the rearward portion thereof, two pulleys at corresponding ends of said guides, two intermediate pulleys at the other ends of said guides, two outer pulleys adjacent the intermediate pulley and a cord passing successively about one outer pulley along a guide, about one of the first named pulleys back along the corresponding guide about one intermediate pulley, about the other intermediate pulley along another guide, about the second of the first

named pulleys, back along the corresponding guide, and about the last named outer pulley to provide two reaches traveling in one direction and two reaches traveling in the opposite direction, the members connected to the forward portion of the seat being movable by reaches of said cord traveling in one direction and the other members being movable by reaches of said cord traveling in the opposite direction.

10 In testimony whereof I have affixed my signature to this specification.

WHIPPLE O. PARROTT.
